United States Patent Office.

HUGH CHRISTIE, OF MORRISANIA, NEW YORK, ASSIGNOR TO ISRAEL FOSTER, OF PHILADELPHIA, PENNSYLVANIA.

Design No. 4,252, dated July 19, 1870.

DESIGN FOR A CARPET-PATTERN.

The Schedule referred to in these Letters Patent and making part of the same.

I, HUGH CHRISTIE, of Morrisania, county of Westester, State of New York, have invented or pro-
ced a Design for a Carpet-Pattern, of which the
lowing is a specification.

The accompanying photographic illustration fully
presents my design, which consists mainly of the
uare or rectangular figures A and B, which over-
each other between the points *x* and *y*, so as to
close square or rectangular spaces C, which are or-
mented substantially as shown.

Each of the figures A and B contains a wreath, *a*,
d each figure has a border, *b*, of the character rep-
ented.

Irrespective of the colors employed,
I claim—

The design for a carpet-pattern, substantially as
described, and as represented in and by the accom-
panying drawing.

In testimony whereof I have signed my name to
this specification in the presence of two subscribing
witnesses.

HUGH CHRISTIE.
